US0D1055626S

(12) **United States Design Patent** (10) Patent No.: **US D1,055,626 S**
(45) Date of Patent: ** Dec. 31, 2024

(54) **ELECTRIC COFFEE GRINDER**

(71) Applicant: **SANTOS**, Vaulx-en-Velin (FR)

(72) Inventor: **Nicolas Fouquet**, Vaulx-en-Velin (FR)

(73) Assignee: **SANTOS**, Vaulx-en-Velin (FR)

(**) Term: **15 Years**

(21) Appl. No.: **35/517,579**

(22) Filed: **May 19, 2023**

(80) **Hague Agreement Data**

Int. Filing Date: **May 19, 2023**

Int. Reg. No.: **DM/229575**

Int. Reg. Date: **May 19, 2023**

Int. Reg. Pub. Date: **Jun. 23, 2023**

(30) **Foreign Application Priority Data**

CLAIM

The ornamental design for an electric coffee grinder, as shown and described.

DESCRIPTION

The patent or application file contains at least one drawing executed in color. Copies of this patent or patent application publication with color drawing(s) will be provided by the Office upon request and payment of the necessary fee.

Electric coffee grinder

1.1: Perspective

1.2: Front

1.3: Back

1.4: Right

1.5: Left

1.6: Top

1.7: Bottom

In reproductions 1.1 to 1.5, and 1.7, the areas colored in yellow show portions of the article that form no part of the claimed design.
